CORNET SUPPORTING STAND

Louis M. Carlini, Paterson, N.J.

Application April 22, 1958, Serial No. 730,218

9 Claims. (Cl. 248—171)

This invention relates to a stand for supporting a musical instrument such as a cornet.

The invention has among its objects the provision of a novel collapsible stand for supporting a musical instrument such as a cornet.

Another object of the invention is the provision of an improved collapsible stand of the type indicated which is simple and rugged in construction, and which is easily collapsed and extended.

Yet another object lies in the provision of an instrument supporting stand which cushions the instrument while the latter is being placed on the stand, and which is cushioned against damage either to it or to the instrument upon the imposition of tipping forces upon the instrument.

The above and further objects and novel features of the present invention will more fully appear from the following detailed description when the same is read in connection with the accompanying drawings. It is to be expressly understood, however, that the drawings are for the purpose of illustration only and are not intended as a definition of the limits of the invention. Reference for this latter purpose being had primarily to the appended claims.

In the drawings, wherein like reference characters refer to like parts throughout the several views,

Fig. 1 is a view in side elevation of an illustrative embodiment of the stand of the invention with a cornet mounted thereon, the wall of the horn of the instrument facing the reader being broken away to show the stand;

Fig. 2 is a view in side elevation of the stand in collapsed condition;

Fig. 3 is an enlarged fragmentary view of the stand in extended condition, portions of the foot members being broken away, the upper portion of the stand being shown in vertical section along line 3—3 of Fig. 5 and the intermediate portion of the stand being shown in vertical section along line 3—3 of Fig. 6;

Fig. 4 is an enlarged fragmentary view of the stand showing its cooperation with the horn of a cornet, certain parts of the stand being broken away;

Fig. 5 is a view in plan of the instrument bracing means of the stand, the view being taken from line 5—5 of Fig. 3;

Fig. 6 is a view in horizontal section through the extended stand, the section being taken along line 6—6 of Fig. 3;

Fig. 7 is a fragmentary view in bottom plan of the extended stand, and

Fig. 8 is a fragmentary view in plan of the extended stand.

The stand of the invention is designed to receive musical horns such as cornets and the like. It is adapted for use by a musician who wishes to support his instrument within easy reach when the instrument is temporarily not being played.

For such purpose, it is desirable that the stand be com-

2

pact even when extended, that it be easily collapsible, and not scratch or mar the instrument. The stand of the present invention combines these characteristics. In addition, it is simple, rugged, is economical to make, and further, provides a desirable cushioning of the instrument as it is placed on the stand, and cushions the stand and instrument against damage from tipping forces applied thereto.

The supporting device of the invention is generally designated by the reference character 10. In Fig. 1 it is shown in operative position, supporting a cornet, which is generally designated 11. The bell mouth portion of the cornet, with which the supporting device coacts, is generally designated 12.

The supporting device has a main column or standard 14 of heavy rod-like form. The lower end of standard 14 has four equally angularly spaced ears 15 thereon, as indicated in Fig. 7, to which are pivotally secured four similar elongated members 16. Members 16 extend generally radially outwardly from the bottom of standard 14 and act as feet when the supporting device is in operative position (Fig. 4) and are folded to extend alongside the standard when the supporting device is collapsed (Fig. 2).

The pivotal connection between each of members 16 and standard 14 is made up of one of the aforesaid ears 15 on the standard, upstanding opposed side flanges 17 attached to the sides of member 16 and receiving an ear 15 therebetween, and a pivot pin 19 extending through flanges 17 and ear 15. For reasons to appear hereinafter, the radially inner ends 20 of foot members 16 extend inwardly beneath the lower end of standard 14 when members 16 are extended in operative position. The pivot pins 19 are preferably so located relative to the lower surface 21 of standard 14 that ends 20 of members 16 engage surface 21 to form a stop against further downward pivoting of members 16 when members 16 have pivoted downwardly slightly past a horizontal position, as shown in Fig. 4. To allow the inner ends 20 of members 16 closely to interfit when extended, they are preferably bevelled, as shown at 22 in Fig. 7.

The foot members 16 are selectively moved into the extended position of Fig. 4 and retracted therefrom into the position of Fig. 2 by the following mechanism. A sleeve member 24 embraces standard 14 and is slidable therewith. Attached to member 24 are the upper ends of four leaf springs 25 which are located in the respective radial planes of the members 16. The upper ends of the springs 25 are disposed in shallow vertically extending grooves in member 24; a ferrule 26 overlies the ends of the springs in such grooves, and it and the ends of the springs beneath it are secured to sleeve member 24 by pins 27.

The lower ends of springs 25, which are curled to provide pin receiving formations 29, are received between opposed upstanding flanges 30 on side plate members secured to the respective foot members 16 intermediate the length thereof. A pivot pin 31 extending through flanges 30 and formation 29 secures the lower end of each spring 25 to its member 16.

The leaf springs 25 connect sleeve member 24 to foot members 16 so that the foot members are extended or retracted simultaneously by movement of the sleeve member downwardly or upwardly, respectively, along standard 14. The springs 25 preferably have a generally straight relaxed configuration, so that when sleeve member 24 is released from the position of Fig. 4 the springs tend to thrust the sleeve member upwardly a substantial extent toward its position in Fig. 2, and in the position of Fig. 2 the springs lie generally flat and close to standard 14. In the extended position of the supporting de-

vice shown in Fig. 4, the springs 25 are resiliently bowed inwardly to a substantial degree, whereby firmly but yieldingly to urge the foot members 16 into their extended position. Sleeve member 24 may selectively be held in its downwardly position (Fig. 4) by a spring biased latch member 32. Member 32 has a body slidable radially of standard 14 in a bore 34 therein, and is urged outwardly by a coil compression spring 35. The nose or outer end portion of member 32 overlies the upper edge of sleeve 24 when the stand is extended, as shown in Fig. 4, thereby retaining the stand in such position. The stand may be released in order to collapse it, by pressing latch member 32 inwardly and sliding sleeve member 24 upwardly past it. Extension of the stand from the collapsed position of Fig. 2 to the fully extended position of Fig. 4 may be effected simply by pulling the upper (Fig. 2) ends of opposite foot members 16 away from each other and then sliding sleeve 24 downwardly along standard 14. A cam groove 36 in the inner surface of sleeve 24 at the lower end thereof in alignment with latch member 32 permits the sleeve automatically to depress the latch member and to ride over it in the downward travel of such sleeve.

As shown most clearly in Fig. 3, the stand of the invention is adapted to receive a bell mouthed musical instrument in upright position, and to retain it stably in such position. The upper end of the standard 14 fits upwardly within the neck of the instrument for a substantial distance, and engages the inner surface thereof to hold the instrument from tipping. The main weight of the instrument is borne by the leaf springs 25, upon which the bell mouth 12 of the instrument rests. In order to steady the instrument and to retain it without tipping, a bracing means generally designated 36 is provided at the upper end of the standard 14 to engage and center the inner wall of the horn of the instrument relative to standard 14. The construction and function of bracing means 36 will be more readily apparent upon consideration of Figs. 3, 4, and 5. As shown in Fig. 3, means 36 is made in the form of a sub-assembly which is secured to the top of standard 14. The sub-assembly has a body 37 having a central stem 39 thereon received in an axial bore 40 in the upper end of standard 14. Body 37 is retained on the standard by a pin 41 extending through it and the stem 39. The upper end of body 37 has three equally spaced longitudinally extending slots 42 therein, as shown in Fig. 5. Such slots receive instrument-bracing spring fingers 44. The lower ends of fingers 44 are firmly secured on body 37 by a sleeve or ferrule 45 overlying them and secured to them and body 37 as by pins (not shown). The outer diameter of ferrule 45 is the same as that of standard 14. The spring fingers are in the form of leaf springs longitudinally curved in section so as to conform generally to the inner surface of the horn of the instrument which they confront.

Fingers 44 have a relaxed shape longitudinally thereof which is shown in Fig. 3. Above the generally straight lower end portion underlying sleeve 45 each finger curves smoothly upwardly and outwardly from the axis of body 37 and then inwardly again, the general shape of the fingers being roughly part-circular. The upper, inwardly directed ends of fingers 44 are spaced somewhat radially outwardly of body 37 when they are relaxed, and lie above the bottom of a central slotted portion 46 at the upper end of body 37. When the fingers are collapsed as shown in Fig. 2 the bodies of the fingers lie mainly in slots 42 and the upper inwardly directed ends thereof lie in slot 46. The relaxed configuration of fingers 44 is such that they then lie somewhat radially outwardly of their positions when operatively engaged with the inner surface of the horn of the instrument (Fig. 4). Thus the fingers resiliently engage the horn to maintain it stably in place on the stand.

The length of the standard 14 is such, and the parts are so arranged that when the stand is collapsed the

sleeve 24 overlies a substantial length of the fingers 44 of bracing means 36, preferably at least to the level at which the fingers lie a maximum distance radially away from the axis of body 37. As a result, the fingers 5 are collapsed into the shape shown in Fig. 2, the outer surfaces of the fingers lying no further outward than the outer surface of sleeve 45.

To prevent scratching and marring of the inner surface of the horn of the instrument, the upper surfaces 10 of springs 25 and the outer surfaces of spring fingers 44 are preferably provided with coatings of soft material such as cork, felt, or the like. In the embodiment shown a coating 47 of cork is cemented to each spring 25, and a layer of cork 49 is cemented to the outer surface of 15 each spring finger 44. Such coating on fingers 44 is further of advantage in providing appreciable friction between the fingers 44 and sleeve 24 to oppose movement of the sleeve downwardly from the collapsed position of the stand shown in Fig. 2. Thus the stand remains 20 stably in its collapsed position until it is deliberately extended. After the sleeve 24 has been moved downwardly on body 37 and standard 14 sufficiently to move below fingers 44, however, the sleeve slides smoothly to permit the facile erection of the stand. Upon release 25 of the sleeve 24 from the position of Fig. 3, the springs tend to straighten and to move the parts toward collapsed position.

As noted in connection with Fig. 3 the bottom surfaces of opposite foot members 16 lie at an angle α with 30 respect to each other when there is no load on the stand. A typical value of α is 177° . Such arrangement is 35 advantageous in that it provides the stand with a cushioning effect when a load such as an instrument is imposed thereon, the foot members 16 then pivoting slightly so that their bottoms lie flat on the floor 50. The springs 25 provide an additional cushioning effect upon the instrument as it is placed on the stand, since they yield somewhat downwardly as they are first engaged by the bell of the horn. Should the stand or the stand with 40 the instrument mounted thereon be subjected to a tipping force applied to the upper end thereof, the foot member or members in line with such force will yield somewhat and pivot upwardly to a small degree about pivot pins 19. This prevents the imposition of damaging forces 45 upon either the stand or the instrument.

Although only a limited number of embodiments of the invention have been illustrated in the accompanying drawings and described in the foregoing specification, it is to be expressly understood that various changes, 50 such as in the relative dimensions of the parts, materials used, and the like, as well as the suggested manner of use of the apparatus of the invention, may be made therein without departing from the spirit and scope of the invention as will now be apparent to those skilled 55 in the art.

What is claimed is:

1. A collapsible support adapted to receive the horn of a musical instrument, said support comprising a vertical standard, a plurality of generally radially disposed foot members spaced angularly about the standard and pivotally connected at their inner ends to the lower end of the standard, a sleeve slidable along the standard above such pivotal connection, elongated leaf spring members interposed between the sleeve and the foot members at locations spaced from the lower end of the standard, stop means to retain the foot members in an extended position, wherein their lower surfaces lie generally in the transverse plane containing the lower end of the standard, and means to retain the sleeve in a lowered position when the foot members are extended, the lowered position of the sleeve being such that the elongated leaf spring members are resiliently bowed inwardly toward the lower end of the standard, the upper 70 surface of said bowed spring members serving to support

the lower bell surface of the horn of an inverted musical instrument.

2. A collapsible support adapted to hold a horned musical instrument in inverted upright position, said support comprising a vertical standard adapted to have the upper end thereof inserted upwardly into the horn of the inverted instrument, a plurality of foot members spaced angularly about the standard and pivotally connected at their inner ends to the lower end of the standard, said foot members being pivotable from a retracted position, in which they lie close alongside and generally parallel to the standard, to an extended position, in which they lie extended generally in the transverse plane containing the lower end of the standard, stop means at the lower end of the standard to retain the foot members in said extended position, a sleeve slidable along the standard, elongated spring members interposed between the sleeve and the foot members at locations spaced from the base of the standard, and means to retain the sleeve in a lowered position when the foot members are extended, the lowered position of the sleeve being such that the elongated spring members are resiliently bowed, the upper surface of said bowed spring members serving to support the lower bell surface of the horn of an inverted musical instrument.

3. A collapsible support as defined in claim 2, said support comprising bracing means disposed adjacent the upper end of the standard and adapted to engage the surface of an inner part of the horn of the instrument when the outer end portion of the horn rests upon said elongated spring members.

4. A collapsible support as defined in claim 3, wherein the leaf spring members are pivotally connected to the foot members, and the connections between the upper ends of the leaf spring members and the sleeve are such that, when the sleeve is in its lowered position, the leaf spring members are bowed inwardly.

30

35

5. A collapsible support as defined in claim 3, wherein the bracing means comprises a plurality of elongated spring fingers attached to the standard and angularly spaced thereabout.

6. A collapsible support as defined in claim 5, wherein the spring fingers are collapsible radially inwardly of the standard, and the sleeve at least partially overlies the spring fingers to collapse them when the sleeve is raised to collapse the foot members.

10 7. A collapsible support as defined in claim 6, wherein the spring fingers have a soft resilient coating on their outer surfaces, such coating having a relatively high coefficient of friction, whereby to serve frictionally to retard the sleeve from downward movement when it is in its upper, stand-collapsed, position.

8. A collapsible support as defined in claim 2, wherein the stop means retains the foot members in their fully extended, substantially unloaded, position in which they extend downwardly past a plane transverse to the standard at a small angle with respect to such plane, such foot member being free to pivot upwardly with respect to the standard in response to the imposition of a force thereto which overpowers its respective leaf spring member.

20 9. A collapsible support as defined in claim 8, wherein said stop means acting between the standard and the foot members are disposed at the pivotal connection between the standard and the foot members.
